UNITED STATES PATENT OFFICE

2,326,135

REMOVABLE ADJUSTING ATTACHMENT FOR
DRAWING COMPASSES AND THE LIKE

Hugo Friedmann, Astoria, N. Y.

Application June 17, 1942, Serial No. 447,354

6 Claims. (Cl. 33—154)

This invention relates to measuring and drawing instruments particularly to those having two jointed legs, like compasses and dividers, and has for its main object to provide an attachment for such instruments whereby they may be adjusted to a desired opening in a more efficient and precise manner than has been done heretofore.

Another object of my invention is to provide an attachment of the mentioned character whereby such instruments may be employed and used by one hand of the operator in the usual manner and with the same one hand they may also be adjusted and set to a desired opening instead of using both hands as it is now necessary for such adjusting of these instruments.

Still a further object of my invention is to provide an attachment as characterized hereinbefore which not only may be set very precisely and exactly to a desired opening with one hand and with great facility, but wherein such adjusting and setting will be done in a mechanical way by a screw and wherein the instrument may be exactly fixed in the position into which it was adjusted and will not and can not change its adjusting and setting during any subsequent operations and uses as long as its adjusting and setting is not changed by the operator.

Still another object of my invention is to provide a device of this type which may be easily attached to such instruments of practically any usual type particularly compasses, and as easily removed therefrom.

Other objects of this invention will be apparent as a specification of the same proceeds and, among others, I may mention: to provide a device of the character indicated which will be simple in construction, inexpensive to manufacture, easy and reliable to apply and to operate, adapted to practically any instrument of the type mentioned, and which will permit wide limits in adjusting the same.

In the drawing forming a part of this specification and accompanying the same:

Fig. 1 is a front elevational view of a pair of compasses with my attachment applied thereon;

Fig. 2 is a side elevational view thereof, and

Fig. 3 is a sectional view on an enlarged scale, the section being taken on the line 3—3 of Fig. 1, a portion of the device being shown without section.

Referring now to the drawing more in detail, by characters of reference, the numeral 10 indicates my novel removable precision adjusting and setting device, as applied on a pair of drawing

compasses, as an example only, generally indicated by the numeral 11.

My device discloses two clamping members 12 and 13, to be applied on the respective legs 14 and 15 of the compasses 11 through the screws 16 and 17, as will be more fully explained herein-after.

The construction of the two clamping members is identical so that a more detailed description of one will suffice.

Referring to the clamping member 12, it is composed of a main body or stem 18, generally of rectangular cross section, which is terminated in upper and lower flanges 19 and 20, turned inwardly, that is, toward the leg of the compasses when the device is secured on such an instrument.

Leg 14 of the compasses will be set into the opening 21 of the channel shaped clamping members 12, and will be secured therein by the screw 16, passing through a threaded hole 22 in the flange 20 and pressing against leg 14 preferable by a plate or washer 23. Screw 16 may be operated by the head disk 24, and when driven inwardly it will press the leg 14 against the opposite flange 19, and, vice versa, when moved outwardly, it will release the leg 14.

A partly screw threaded hole 25 is provided through the upper flange 19 and a pin 26 is rotatably arranged therein, its screw threaded inner end 27 being in engagement with the screw threaded inner portion of the hole 25.

A ring 28 is secured on the outer end of the pin 26, or these two parts may be made integral, in one piece, the hole 29 in the ring 28 being screw threaded in a certain direction, let us say, as for a right handed screw.

The other channel form clamping member 13 is identical with member 12, just described, with the exception that its securing screw 17 may be made considerably shorter than the screw 16 so that its head disk 24a may be easily operated without interference by the head 24 of screw 16, and that its ring 28a is oppositely screw threaded to that of ring 28, that is, in a left handed direction in this case.

An elongated screw 30 is passed through the rings 28 and 28a having a transverse knurled disk 31 of a comparatively large diameter secured at its center, the screw threads on its left hand portion 32 obviously being the same as those in the ring 28 and cooperating therewith, while the screw threads on its right hand portion 33 being oppositely directed and cooperating with the threads in ring 28a.

The use and operation of my device will be un-

derstood from the description thereof by those versed in this art, but I may offer the following further explanation relating thereto:

As has been mentioned, my attachment may be a separate unit, applied to, or removed from, any suitable instrument, as desired, but it also may be a permanent part of such instruments and built into the same when it is originally manufactured.

The use and operation of the removable or of the permanent forms of my attachment obviously is the same.

The embodiment described, and shown in the drawing, is a detachable one, and is applied on a pair of drawing compasses of the most usual type.

The openings 21 in the respective channel or U shaped clamping members 12 and 13 are of such a shape and size that they conveniently receive the legs of any usual drawing compasses, dividers, or other similar instruments.

In the instant case, clamping member 12 will be placed on or over a selected portion of leg 14 and secured thereon by the suitable turning and inward moving of the screw 16.

Similarly, clamping member 13 will be placed on leg 15 and secured thereon by the screw 17, care being taken to place the two clamping members in the right position on the respective legs, viz, at the same distance from the pivot or joint 34 of the legs.

Now, upon turning screw 30 in one or in the other direction, by the manipulating knurled disk 31, the opposite screw threads 32 and 33 will in one case cause the rings 28 and 28a to move inwardly, toward one another, or, in the other case, outwardly, away from one another. The movement of the rings 28 and 28a will carry the respective legs 14 and 15 in a similar manner so that the opening of the pair of compasses 11 will be reduced or increased.

It will be obvious that the device is dimensioned in such a manner that the compasses may be moved to the smallest limit, that is to zero distance, the two legs touching each other, or in the opposite direction, the rings 28 and 28a may be moved to the terminations 35 and 36 of the screw 30 thereby setting the legs 14 and 15 to the greatest opening, which may be as large as may at any time be needed in the usual application of the instrument. The range of the opening will depend on the length of the screw 30.

I preferably leave a small space 28b between the tops of the clamp members 12 and 13 and the rings 28 and 28a to permit an easier adjusting of the rings to the angles of the legs 14 and 15 as they are closing or opening.

It also will be obvious that the hand operating the compasses may use one finger, or the thumb, for turning the disk 31, so that the instrument may be used and may be regulated and adjusted, simultaneously, and both with the one hand of the operator.

The present many vacillating trials and uncertainty in setting such an instrument, even while both hands are needed to move the two legs closer or further away, is eliminated, with my attachment, the adjusting of the instrument to any desired distance will be easy, convenient, automatic, mechanical, gradual, positive and precise, and the hand operating the instrument will be able to do the adjusting, too. The adjusting, therefore, not only will be more handy and precise but it will also leave the other hand free.

The adjustment also may be made without re-

moving the instrument from the job, only slightly lifting one leg, and keeping the other at the desired spot, while, of course, the whole instrument may be lifted off the job, somewhat, and the disk 31 turned in such a position if that is desired.

The setting is extremely fine and gradual so that no repeated trials are needed, the instrument is moved unhesitatingly to the right position in one continuous movement and the setting may at once be made just the right one to the finest degree, as will be obvious. Indeed, I may call it a "micrometer setting," right in a drawing or measuring instrument, if the screw threads 32 and 33 are made fine enough.

Once the instrument is set by my attachment, it will be locked in such a position, and it will be insured that its distance will not change as long as the operator does not change it by the use of the manipulating disk 31, the present danger of the instrument moving and changing after an adjustment is, therefore, entirely eliminated when my attachment is used thereon.

This is especially important when it is desired to repeatedly mark the same distance.

It also will be obvious that my attachment may be used on other instruments than of the jointed leg type as long as they have two measuring or drawing elements which move toward or away from one another for setting. The manipulating disk 31 also may be arranged in other appropriate positions than in the middle of the screw 30, like at an end thereof.

My invention may be applied to practically any instrument of this type as it will be easy to secure its two clamping members on the moving measuring or drawing elements and it may be used on drawing and shop instruments, as an example, the use of the large wooden compasses for drawing on a blackboard in school rooms will be greatly facilitated, for which purpose my attachment may be made of wood too, with steeper screw helices for quick adjusting.

Through the use of my attachment any pair of compasses may be made into a precision instrument, even the cheapest school sets, and a worn, faulty instrument, shaky and with plenty of lost movement, may be made firm and exact.

Compasses with my attachment will be very useful when it is desired to draw several very close, hairline, circles from one center, which through it may be done without lifting the pointed end of the instrument from said center.

It will be seen that I have shown and described an attachment for drawing and measuring instruments embodying the principles and attaining the mentioned objects of the present invention.

Since many matters of operation, interaction, combination, arrangement and structure may be variously modified without departing from the inventive principles herein, it is not intended to limit the invention to the details of the present embodiment, and I desire to reserve my rights to all changes and modifications as are within the spirit of this specification and within the scope of the claims hereunto appended.

What I claim as new and want to protect by a patent of the United States, is:

1. In an adjusting and setting attachment for drawing and measuring instruments, like compasses and dividers, having two joined legs, and a rod having opposite threads at its two sides from about its center, whereby to cause said legs to move closer to or further away from one

another, a U shaped member embracing each leg, means to removably secure one of the flanges of the U in each member on the respective leg, and oppositely screw threaded openings in said members for the respective threads of said rod.

2. In an attachment, as set forth in claim 1, a rotatable pin projecting outwardly from the other flange of each member, a ring at the free end of said rotatable pin, said screw threaded openings being in said rings.

3. In a device to set two movable elements closer to or further away from one another, having oppositely screw threaded holes, and an oppositely threaded rod passed through both holes, whereby to cause said two elements to move closer to or further away from one another, a U shaped member embracing each element, means to removably secure one of the flanges of the U in each member on the respective element, said holes being arranged on said U shaped members.

4. In a device, as set forth in claim 3, a rotat-

able pin projecting outwardly from each member, a ring on the free end of each pin, said oppositely screw threaded openings being in said rings.

5. In a device, as set forth in claim 3, a rotatable pin projecting outwardly from each member, a ring on the free end of each pin, said oppositely screw threaded openings being in said rings, said removable securing means for the U shaped members on the respective elements being in the form of a screw passing through one of the flanges of the U, and engaging the respective element, and said pins being arranged in the other flange of the U shaped members.

10 6. In a device, as set forth in claim 3, a rotatable pin projecting outwardly from each member, a ring on the free end of each pin, said oppositely screw threaded openings being in said rings, said pins being inwardly or outwardly movable to adjust the distance of said rings from the recess in said U.

HUGO FRIEDMANN.
